UNITED STATES PATENT OFFICE.

BENJAMIN F. MAYO, OF SALEM, MASSACHUSETTS.

WORK-CLAMP.

1,174,751.

Specification of Letters Patent.

Patented Mar. 7, 1916.

Original application filed June 9, 1910, Serial No. 565,962. Divided and this application filed September 17, 1914. Serial No. 862,204.

To all whom it may concern:

Be it known that I, BENJAMIN F. MAYO, a citizen of the United States, residing at Salem, in the county of Essex and State of Massachusetts, have invented certain Improvements in Work-Clamps, of which the following description, in connection with the accompanying drawings, is a specification, like reference characters on the drawings 10 indicating like parts in the several figures.

This invention relates to devices for positioning relatively to each other the parts of work that are to be subsequently united by sewing, or other fastening-inserting mechanism, and for maintaining the parts in correct relation during such operation, this application being a division of my application filed June 9, 1910, Serial No. 565,962.

An important object of the present invention is to provide means for insuring the proper arrangement of the parts of a shoe upper on a form so that said parts will be in position for subsequent connection by stitches, or other permanent fastenings, and 25 after so arranging said parts to hold them firmly in assembled relation during the operation of the sewing, or other fastening-inserting machine, by which they are connected.

While in the embodiment of the invention herein illustrated the mechanism for positioning and holding the work is constructed especially for use in connection with the parts of shoe uppers, and it is with reference to such shoe parts that many features of the invention will be found to possess the greatest advantages, some features of the invention will obviously be found of value to facilitate the assembling and holding together of the parts of other kinds of work that are to be secured together. For this reason certain of the claims hereinafter made do not limit the features and combinations to which they are directed to use in connection with the elements of shoe uppers.

Having in view the above, and other objects, an important combination of the present invention consists in a form constructed to predetermine the relative position of the

parts of the work which are to be subsequently connected, and means for holding the parts in assembled relation while they are being united by a fastening-inserting mechanism. In the illustrated construction, the form is shaped for holding the parts of shoe uppers and the holding means is a clamp which is shaped to embrace the work-holding form. Preferably the form is adjustable to accommodate different-sized shoe uppers, and in connection therewith a carrier having a series of adjustable gage pins is employed, the pins being adapted to project through the cyeleted openings in shoe quarters. The two lowermost pins serve to position the rear edge of the front of a vamp, while the lower edges of the sides of the vamp are supported by an adjustable member which positions the upper edges of the vamp relatively to the lower edges of quarters to which they are to be connected. Other pins, projecting from the side of the form, serve to sustain the lower edges of the quarters.

In operation, the parts of the upper are first positioned by the devices referred to, and are then held in such position by the removable clamp which is constructed to be taken from the form with the assembled shoe parts and applied to a sewing, or other suitable machine, where the shoe parts will be joined by permanent fastenings.

Other features of the invention than those above referred to, including important details of construction and combinations of parts, will be hereinafter more particularly described and claimed.

In the drawings: Figure 1 is a view in side elevation of a shoe form and clamp with the parts of an upper clamped in assembled relation on the form. Fig. 2 is a view in side elevation of the form shown in Fig. 1, without the clamp, and illustrating certain details not visible in Fig. 1. Fig. 3 is a view in cross-section on the line $x-x$, Fig. 2. Fig. 4 is a detail view, showing in perspective the gage pins for locating the rear edge of the front part of a vamp and for holding the lower front edges of the quarters together,

and Fig. 5 is a detail view, showing a clamp for holding the uppers of button and other shoes.

The embodiment of the invention illustrated herein, includes a form and clamp which are designed for positioning and holding together vamps and quarters. The base or pedestal 147, supports a form comprising a forepart, 145, and a heel part, 151, 10 said parts being preferably rotatably supported on the base. The heel part is shown as being provided with guide rods 155, 156, to slidably engage suitable ways in the fore-part and thereby permit longitudinal 15 adjustment of the heel part, and a bell-crank lever, 157, having one arm connected by a link, 159, with the heel part and its other arm connected by a rod, 161, or the like, with a treadle, serve as a means for 20 moving the heel part rearwardly. The heel part is moved forwardly by any suitable means, as, for instance, a spring 163, which may be connected at one end to the rod 161, and at its other end to a fixed point on the 25 fore part, as shown. At suitable points in the sides of the heel part, openings are formed to slidably receive the pins 165, which are normally projected beyond the surface thereof by yielding means, as 30 springs. An externally threaded rod, 167, is rigidly connected with the heel part and projects downwardly therefrom, and a bar 169 having a sleeved-extension, 170, to fit said rod, is arranged below the heel part 35 and adjustably sustained relatively thereto by a thumb-nut 171, which is in threaded engagement with the rod.

The fore part is formed with openings, 173, through which project positioning pins, 40 175, carried by transversely slideable blocks, 177, which are arranged for adjustment in a frame, 174, by the reversely threaded screws, 179. The blocks also have threaded engagement with a screw 181 by which 45 they may be adjusted longitudinally in the frame 174. This frame is shown as being provided with an extension, 182, which may be attached to the fore part by a screw, as shown by dotted lines in Fig. 2. The fore 50 part may also be formed or provided with an arm, 153, to whose extremity is connected by a clamping bolt, 184, a clamp 183, carrying spaced arms, 185, covered with some soft material and adapted for engagement with the lower front portion of the 55 quarters of a button boot or shoe to hold the same in position on the form. The clamping members 187 and 189 are arranged to be placed over the parts of the 60 form, and the shape of these members is such that they will snugly fit over a vamp placed on the form, as shown in Fig. 1. In order that the clamp members may be capable of longitudinal adjustment to accommodate 65 vamps of different sizes, their ends are

arranged to overlap at a point located preferably about midway of the form, and one of the members is provided with slots, 191, and the other member with clamping bolts 193, to enter the slots and with winged nuts 70 engaging the bolts, whereby the members may be held in their different positions of adjustment. A stud 192, extending from a point near each end portion of the member carrying the clamping bolts, and respectively entering the slots 191, serve, in connection with the bolts 193, to maintain the two members of the clamp in parallelism during such adjustments. The clamp members are preferably provided with brackets, 75 or other suitable supports for a guide bar 195, which is divided at a suitable point and has its ends connected by a telescopic or similar sliding joint, 196, and a guiding flange, 197, which is similarly divided and 80 has its ends arranged to overlap, as shown at 198, is also supported from the members, the flange being preferably located, approximately, at the uppermost edge of the members, as will be seen in Fig. 1. The 85 described construction of the bar 195 and flange 197 permit longitudinal relative movements of those parts as the clamp members upon which they are carried are being adjusted without disturbing their relation 90 to said members, and in a manner that will be readily understood. A plurality of U-shaped spring bars 201, are arranged to cooperate with the clamp members 187, and 189, in holding the vamp and quarters in 100 position to be sewed together after they have been assembled on the form. These bars are each constructed at one end for detachable engagement with a slotted head, 105 210, which is held and guided in proper relation to the clamp member by a pin, 209, extending from said member and entering a slot or opening in the head, and by other pins, 207, projecting laterally from opposite sides of the head, and movable between the 110 arms of staple-shaped guides 205, supported by the clamp member. A cam 203, is connected pivotally with the head and constructed and arranged for engagement with the clamp member to force the lower limb 115 of the spring bar against certain parts of the vamp and quarters in order to clamp them firmly between the limb of the bar and the clamp member. Preferably, a spring bar carrying a cam as described is located 120 at the center of the fore part, at the center of the heel part, and upon opposite sides of the vamp between the ends thereof, in order to clamp the vamp and quarters to each other at suitably spaced points, as 125 shown in Fig. 1. The spring bar which is located at the fore part is shown as having its lower limb provided with a bearing plate 202, which is designed to engage the lower 130 extremities of the extreme front edges of

the quarters, and to coöperate with the rear edge of the clamp member 187 at this point in clamping the vamp and quarters tightly together. To accommodate this plate, the 5 form is constructed with the opening 176, as shown in Fig. 2.

In the operation of assembling and clamping together a vamp and quarters with the 10 devices just described the parts of a shoe quarter are placed on the form with their lower edges resting on the pins 165, and the pins 175 are inserted in eyelet holes near the lower front edges of the quarters, as shown in Fig. 1, which properly 15 locates the quarters on the form. The rod 161 is then depressed to the desired degree by a foot treadle, or other suitable means, which, through the described connections, moves the heel part of the form to the rear 20 sufficiently to straighten the quarters and smooth out all the wrinkles. A vamp, with the rear or heel portion sewed up, is then placed over the quarters and positioned on the form with its lower edges resting upon 25 the bar 169, (see Fig. 3) and the operator pulls the vamp at the toe in a forward direction to straighten out the vamp, particularly along the upper edge. Prior to this 30 step in the assembling operation the quarters were supported upon the plungers 165 which served to locate their lower edges properly with respect to the upper edges of the vamp in order to provide the proper amount of overlap. The act of pulling forward the 35 vamp at the toe causes the vamp to hug the sides of the form tightly and forces the pins 165 in against their springs, whereby the overlapped portions of the vamp and quarters are permitted to contact with each other 40 in the proper relation. The clamping members 187, 189, are then placed over the vamp and quarters as shown in Fig. 1, the spring bars 201 are inserted in position, and the cams 203 operated to tightly clamp the 45 vamp and quarters between the lower limbs of the spring bars and said members, the operator turning the form on its base during such operations in order to present the same in the most convenient position for 50 the several described manipulations.

It will be observed that the ends of the inner limbs of the spring bars and the adjacent coöoperating edge of the clamping members clamp together the overlapped 55 edges of the vamp and quarters after these parts are properly positioned on the form. All of these parts of the clamp, together with the work, may then be removed from the form, which is provided with suitable 60 vertical openings to permit the free passage of the bars 201 therefrom in an upward direction. The work as thus positioned and held together is now ready for application to the sewing, or other fastening inserted 65 machine, whose construction and mode of

operation in connection with this embodiment of the invention may be substantially like that described in my co-pending application, Serial No. 565,962, heretofore referred to.

Where the positioning and clamping devices are used in connection with vamps for button shoes, the quarters may be buttoned at the lower portion thereof; the pins 175, inserted in a suitable number of the button 70 holes, the clamp 183 lowered into a position to properly engage the upper and hold it, and a spring 220, (see Fig. 2) having one end secured to the arm 153 and its other end secured to the clamp at a suitable point 75 beyond the bolt 184, may be employed to hold the clamp raised above the form, or in clamping position upon the upper, as desired.

Having thus described my invention, what 80 I claim as new and desire to secure by Letters Patent of the United States is:

1. The combination with a shoe form, of means associated therewith for determining the relative positions of a plurality of parts 90 of an upper on said form, and a clamp for holding said parts together in the positions determined by said means while they are being united by stitch-forming mechanism.

2. The combination with a shoe form constructed to receive the parts of an upper, of means carried by the form adapted to determine the relative positions of said parts, and means for holding said parts together 100 in such relative positions while they are being united by stitch-forming mechanism.

3. The combination with a shoe form, of means thereon for determining the relative positions of a plurality of parts of an upper to be secured together, and means for holding 105 said parts in such assembled relation on the form and while they are being united by sewing mechanism and adapted for removal with the work from the form to such sewing mechanism.

4. The combination with a shoe form, of means for determining the relative positions of the parts of a shoe upper on said form, and a clamp for holding said parts as thus positioned constructed for removal 115 with the clamped work from said form.

5. The combination with an adjustable shoe form provided with means for determining the relative positions of the parts of a shoe upper thereon, of an adjustable 120 clamp to engage said parts while on the form, said clamp being arranged for removal with the clamped work from the form.

6. The combination of a support, a shoe 125 form rotatably carried thereby, means on said form to determine the relative positions of the parts of a shoe upper, and a clamp to hold said parts in such assembled relation.

7. The combination with a shoe form, of means thereon to sustain a vamp and quarters by their edges constructed and arranged to determine the relative positions of said parts preliminary to the operation of sewing them together. 70
8. The combination with a shoe form, of means to sustain a vamp and means to sustain quarters with the edges of said parts in overlapped relation, one of said means being adjustable for causing relative movement of the vamp and quarters to control the extent to which their edges are overlapped. 75
- 10 9. The combination with a shoe form, of adjustable means for sustaining a vamp by one edge and means for sustaining quarters with their edges in overlapped relation to the other edge of the vamp. 80
- 15 10. The combination of a shoe form, a rod depending therefrom, a transversely extending bar movable on said rod and arranged to support a vamp, a nut threaded to said rod below the bar for adjustably sustaining the same, and means for supporting quarters located above said bar. 85
- 20 11. The combination with a shoe form, of devices carried thereby and adapted to enter openings in quarters, said devices being constructed and arranged to determine the position of the edge of a vamp relatively to said quarters. 90
- 25 12. The combination with a shoe form, of devices carried thereby adapted to enter openings in quarters and means for locating the edge of a vamp relatively to said quarters, means for sustaining a vamp, and means for sustaining quarters. 95
- 30 13. The combination with a form constructed to receive the parts of a shoe upper, of means thereon to determine the positions of said parts, and a clamp to engage said parts while on the form and hold them together, the form being constructed to permit the removal therefrom of the work while clamped. 100
- 35 14. The combination with a shoe form, of means thereon to support a vamp, and yielding devices located on opposite sides of the form and arranged to normally project for supporting the lower edges of the quarters a suitable distance below the upper edge of the vamp, the parts being so arranged that when the vamp is pulled longitudinally said devices will yield and thereby permit engagement of the adjacent edges of the vamp and quarters. 110
- 40 15. The combination with a shoe form, of devices carried thereby for determining the relative positions of a vamp and quarters on said form, and clamping means shaped to fit over and embrace the form and to engage the vamp and hold the vamp and quarters in assembled relation. 115
- 45 16. The combination with a shoe form, of devices carried thereby for determining the relative positions of a vamp and quarters on said form, and clamping means shaped to fit over and embrace the form and to engage the vamp and hold the vamp and quarters in assembled relation, said clamping means having capacity for adjustment. 120
- 50 17. The combination with a shoe form, of devices carried thereby for determining the relative positions of a vamp and quarters on said form, and clamping means shaped to fit over and embrace the form and to engage the vamp and hold the vamp and quarters in assembled relation, said form and clamping means being adjustable. 125
- 55 18. The combination with a shoe form, of devices thereon to support the lower edges of quarters, and means to support a vamp on the form arranged for adjustment to position the upper edges of the vamp in overlapping relation to the quarters. 130
- 60 19. The combination with a shoe form, of yielding devices thereon to support the lower edges of quarters, means to support a vamp on the form arranged for adjustment to position the upper edges of the vamp in overlapping relation to the quarters, and clamping means constructed to fit over the form and hold the vamp and quarters in assembled relation. 135
- 65 20. The combination with a shoe form, of yielding devices thereon to support the lower edges of quarters, means to support a vamp on the form arranged for adjustment to position the upper edge of the vamp in overlapping relation to the quarters, and clamping means constructed to fit over the form and hold the vamp and quarters in assembled relation, said clamping means being arranged for removal from the form with the clamped work. 140
- 70 21. A form adapted for use in assembling the parts of shoes having means to determine the relative positions of said parts, and means removable with the assembled parts from the form for holding them together. 145
- 75 22. A curved form constructed in semblance of the finished article and adapted for use in assembling parts which are to be connected, said form being constructed to determine the relative position of said parts prior to their connection, and means having a curved conformation to agree with the portion of the form over which it is placed and extending around said form for clamping the parts of the work in the predetermined relative position after they have been assembled. 150
- 80 23. A form adapted for use in assembling parts which are to be connected and constructed to determine the relative position of said parts prior to their connection, and means for clamping the parts in assembled relation on the form and adapted for removal with the work so held. 155

24. A shoe form for use in assembling parts of an upper, said form being constructed to determine at a plurality of points the amount of overlap of the parts for attachment together. 70
25. A shoe form for use in assembling parts of an upper, said form being constructed to determine at a plurality of points the amount of overlap of the parts for attachment together, and a clamp to secure said parts in assembled relation while they are so positioned. 75
26. A shoe form for use in assembling parts of an upper, said form being constructed to determine the relative positions of the vamp and quarters for attachment together, and means adapted to maintain the parts of the upper in assembled relation to one another and for removal with the upper 80 from the form while so holding the work.
27. The combination with a shoe form for positioning relatively a vamp and quarters, of a clamp comprising members constructed to fit over the form and jaws to coöperate with said members in holding the vamp and quarters in assembled relation. 85
28. The combination with a shoe form for positioning relatively a vamp and quarters, of a clamp curved to fit over and embrace said form and to engage the vamp and hold the vamp and quarters in assembled relation. 90
29. The combination with a shoe form for positioning relatively a vamp and quarters, of a clamp comprising adjustable members shaped to fit about the form, and cam-actuated jaws to coöperate with said members in holding the vamp and quarters in assembled relation. 95
30. The combination with a shoe form for positioning relatively a vamp and quarters, of a clamp comprising longitudinally adjustable members constructed to fit about the form, and jaws to coöperate with said members constructed to clamp the parts in yielding engagement with the members. 100
31. The combination with a shoe form for positioning relatively a vamp and quarters, of a clamp comprising members constructed to fit about the form, resilient jaws to co- 105 operate with said members, and cams to actuate said jaws.
32. The combination with an adjustable form for positioning relatively the parts of shoe uppers, of an adjustable clamp arranged to fit over the form and hold the upper parts in assembled relation, said clamp being removable with the work from the form. 110
33. The combination of a form for positioning the parts of shoe uppers, of a clamp for holding said parts in assembled relation, and means on said clamp for guiding the work relative to stitch forming mechanism. 115
34. The combination with a form for po- 120
- sitioning the parts of shoe uppers, of means adjustably supported from the form and constructed to engage the lower front portion of the quarters of a button shoe to clamp it on the form. 125
35. The combination with a form for positioning the parts of shoe uppers, of a clamp supported pivotally from said form and having spaced arms to engage the lower front part of the quarters of a button shoe to hold the same on the form. 130
36. The combination with a form for positioning the parts of shoe uppers, of a clamp supported from said form and having spaced arms to engage the lower front part of the quarters of a button shoe and hold it on the form, and a clamping bolt for adjustably connecting the clamp to said extension. 135
37. The combination with a shoe form comprising a fore part and a heel part, of a clamp comprising adjustably connected members constructed to hold the vamps and quarters of shoes in assembled relation on said form, and means to cause relative longitudinal movement of the form parts in fitting parts of shoes thereto. 140
38. The combination with a shoe form comprising a fore part, and a heel part supported for adjustment relative to the fore part, of treadle actuated means for separating said parts, yielding means for moving said parts together, and a clamp to fit over the form, and hold the parts of an upper in assembled relation thereon. 145
39. The combination with a shoe form comprising a fore part, and a heel part having means to slidably engage the fore part, of treadle-actuated means for separating said parts to stretch an upper on said form, means to reversely move said parts, and a removable clamp to hold the parts of the upper in assembled relation on the form. 150
40. The combination with a shoe form, of means for positioning quarters thereon comprising pins to enter eyelet holes near the lower front edge of the quarters, and means to effect simultaneous adjusting movements of said pins toward and from each other. 155
41. The combination with a shoe form, of means for positioning quarters thereon comprising pins to enter eyelet holes near the lower front edges of the quarters, and means to adjust said pins longitudinally of the form. 160
42. The combination with a shoe form, of pins arranged to enter eyelet holes near the lower front edges of quarters on said form, and means permitting transverse and longitudinal adjustments of said pins. 165
43. The combination with a shoe form, of means thereon to support a vamp, and devices located on opposite sides of the form and arranged to normally project for sup- 170

porting the lower edges of the quarters a suitable distance below the upper edge of the vamp, the parts being so arranged that when the vamp is pulled longitudinally said devices will permit engagement of the adjacent edges of the vamp and quarters.

5 In testimony whereof I have signed my

name to this specification in the presence of two subscribing witnesses.
